UNITED STATES PATENT OFFICE.

ANDREW WOLLENSAK, OF ROCHESTER, NEW YORK, ASSIGNOR TO WOLLENSAK OPTICAL COMPANY, OF ROCHESTER, NEW YORK, A CORPORATION OF NEW YORK.

IRIS DIAPHRAGM.

Original application filed July 29, 1920, Serial No. 399,939. Divided and this application filed December 4, 1920. Serial No. 428,356.

To all whom it may concern:

Be it known that I, ANDREW WOLLENSAK, a citizen of the United States, and resident of Rochester, in the county of Monroe and State of New York, have invented certain new and useful Improvements in Iris Diaphragms, of which the following is a specification.

The present invention relates to iris diaphragms, this application being a division of an application filed by me on the 29th day of July, 1920, Serial No. 399,939, an object of this invention being to improve the construction of the iris diaphragm so as to make it easier to assemble and not so liable to get out of order. A further object of the invention is to provide a ring interposed between the two rings of the diaphragm and acting to hold the opposite ends of the blades in cooperative relation with the two rings.

To these and other ends the invention consists of certain parts and combinations of parts, all of which will be hereinafter described, the novel features being pointed out in the appended claims.

In the drawings:

Figs. 1 and 2 are views of opposite sides of the iris diaphragm removed from the casing, parts being broken away or removed for the purpose of better illustration;

Fig. 3 is a detail view of the iris supporting plate;

Fig. 4 is a detail view of the spring ring;

Fig. 5 is a detail view of the operating ring of the iris diaphragm;

Fig. 6 is an enlarged sectional view through the iris diaphragm.

The iris diaphragm in the illustrated embodiment comprises a plate formed with a ring or annular central portion 4 and supporting lugs 5 projected from opposite sides thereof, the supporting lugs being deflected in a plane at one side of the annular central portion 4. Also projected from the periphery of the annular central portion are spaced lugs 6, these lugs also lying in a plane to one side of the annular central portion with the supporting lugs 5. In the spaces between these lugs 6, one of the ends of the iris blades 7 are mounted, the lugs 5 also having openings 8 formed therein for the mounting of two of the blades. In order to hold these ends of the blades

in the spaces between the lugs 6 as well as 55 to hold the opposite ends of the blades, a thin flexible ring 9 is provided formed with a pressed up annular rib 10 on one face. The opposite face of the ring abuts the side faces of the lugs 6 so that the ends of the 60 blades will be held in the spaces between said lugs. The opposite ends of the blades are extended through the ring 9 and cooperate with the opposite face of said ring 9, said ends also projecting into openings 11 65 formed in the operating ring 12, the operating ring having an annular projection 13 on its face opposed to the annular projection 10 on said ring 9 and intersecting the openings 11 so that the ring 9 with said 70 projection 13 will hold the ends of the blades in the openings while permitting the turning of the operating ring to shift said ends in order to open and close the iris. Overhanging projections 14 are pivotally 75 mounted by eyelets 15 on the lugs 5 and are adapted to swing over the operating ring so as to hold said operating ring as well as the ring 9 to the supporting iris plate. Some of the lugs 6 may be provided with laterally 80 deflected portions 16 for the purpose of guiding the operating ring 12 in its rotary movement. The rotary movement of the operating ring may be effected by two lateral extensions 17 and 18, which may also 85 serve as a means for indicating the position of the blades of the iris diaphragm.

This form of iris diaphragm adapts itself particularly for the building of the iris diaphragm independently of the shutter 90 casing and thereafter to the installation of the same in the casing in completed form. The lugs 5 form means for attaching the iris diaphragm to a suitable support. It is apparent that the construction of the iris 95 diaphragm permits the latter to be assembled independently of the shutter casing and thereafter to be fitted to the casing in its assembled form. A ring is provided between the two rings of the iris diaphragm, 100 which acts to hold the blades in cooperative relation at opposite ends with the rings, thus dispensing with pivot pins for the blades of the iris diaphragms.

What I claim as my invention and desire 105 to secure by Letters Patent is:

1. An iris diaphragm comprising two relatively rotatable rings, a blade retaining ring

interposed between the rings, and blades, each extending through the retaining ring and held at one end between the retaining ring and one of the first named rings and 5 at the other end between the retaining ring and the other of the first named rings.

2. An iris diaphragm comprising two relatively rotatable rings, one of which has offset portions on one side thereof, a blade 10 retaining ring supported between said first named rings and resting upon said offset portions, and blades, each extending through the retaining ring and held at one end be-

tween the retaining ring and one of the first named rings and at the other end between 15 the retaining ring and the other of the first named rings.

3. An iris diaphragm comprising two rings each provided with openings, blades having their ends received within the openings of both rings, and a ring interposed between the first mentioned two rings and 20 acting to hold the blades in the openings of such rings.

ANDREW WOLLENSAK.
